OUTLET FOR BASEBOARD RACEWAYS

Filed July 28, 1928

UNITED STATES PATENT OFFICE

PAUL H. LACEY, OF CHICAGO, ILLINOIS

OUTLET FOR BASEBOARD RACEWAYS

Application filed July 28, 1928. Serial No. 295,873.

This invention relates to outlets for base board raceways, and its principal object is to provide simple means whereby electric conductor cord extensions may be run from the 5 raceway of base board constructions to any desirable place within the room. In modern buildings a raceway is provided behind the base board for the reception of electric conductor cords, but so far as I am aware, no 10 outlet devices have been provided for the passage of conductor cords from the raceway to the interior of the room. Usually the plaster is chipped away, or the base board is cut away, or some other make-shift outlet has 15 been provided at the place or places where it was necessary to run a conductor cord extension from the raceway to the interior of the room.

In accordance with the present invention,
20 the base board is provided at a plurality of
places along its length with outlet devices
concealed by the surface finish of the wall
and having a "knockout" place which may
25 be opened to permit the passage of a conduc-
tor cord therethrough. The invention con-
sists in the several novel features hereinafter
fully set forth and claimed.

The invention is clearly illustrated in the drawing accompanying this specification in which—

Figure 1 is a perspective view, partly in section, of a fragment of a wall and base board construction, and showing one of the outlet devices applied thereto;

35 Fig. 2 is a front elevation of a fragment of the parts seen in Fig. 1 with the base board removed;

Fig. 3 is a vertical cross section taken on the line 3-3 of Fig. 2;

49. Fig. 4 is a fragmental vertical longitudinal section taken on the line 4—4 of Fig. 3;

Fig. 5 is a perspective view of one of the outlet devices; and

45 Referring to said drawing, the reference
3,311,310, indicates a fragment of a wall

character 5 designates a fragment of a wall or partition of a room, 6 designates the floor, 7 and 8 designate the upper and lower ground strips which are secured to the wall in any

suitable manner, and 9 designates the base board which is usually secured to the upper ground strip by screws or the like 10, with its lower edge removably held in a shoe 11. The plaster 12 extends up from the upper ground strip 7, and its surface is made flush with the front face thereof.

Between the wall 5, base board 9 and upper and lower ground strips 7 and 8 is a race-way 13 for the reception of electric conductor cords 14, which conductor cords may be lead through said raceway around the room, or from room to room through the partition. A base board construction of the character described and containing a novel incorner construction is more fully shown and described in my Patent No. 1,652,282, dated December 13, 1927, for improvements in incorner retainer strips, and the outlet forming the subject matter of this specification is designed for use in connection with the type of base board construction disclosed in said invention, but obviously it may be employed in connection with other forms embodying a race-way for conductor cords.

The outlet device 15 is preferably formed of a piece of sheet metal struck up with suitable dies to give it the form illustrated particularly in Fig. 5. As shown, the outlet device 15 comprises spaced tongues 16 and 17 connected by a hood-like portion 18, the tongue 16 being formed with one or more "knockout pieces" 19 located in that portion of the tongue 16 which forms the front of the hood 18. The hood portion has a top wall 20 and end walls 21 which extend between the side edges of the tongues. This construction provides an open space between the tongues 16 and 17 and a passage through the hood and out through the knockout opening designated by 19^a. The outlet device is substantially of the same width as the upper ground strip 7 and the tongues 16 and 17 may converge slightly towards each other from top to bottom, so that they will grip the ground strip between them when placed thereon, as seen in Fig. 3.

At the places where the outlets are provided for the raceway, (and there may be three or four such places along the base board of a 100

room, or as many as desired, the upper ground strip 7 is formed with vertical grooves or channels 22 in its front face, and the outlet devices 15 are placed upon the upper ground strip at places over the grooves after the ground strip has been secured in place on the wall of the building, but before the room is plastered. The tongues 16 and 17 frictionally hold the outlet device upon the ground strip, but if it is desired to more permanently secure it thereto, the tongue 16 may be provided with perforations 23 through which small tacks or brads 24 may be driven into the ground strip.

After the outlet devices have been secured in place, the walls are plastered as usual, the plastering extending over the hood 18 and enclosing the same. When the room is trimmed, the base board is secured in place as usual, and the conductor cords for telephones, signaling apparatus and other electrical devices may be placed in the raceway behind the base board. Wishing to extend one of the conductor cords from any of the outlet devices, the base board is temporarily removed and the knockout piece 19 broken away to leave the outlet opening 19^a after which a conductor cord may be passed from the raceway and up through the groove or channel 22 into the interior of the hood 18 and out through the outlet opening 19^a from which it may be extended to any desired place in the room. The base board is then replaced.

It will be observed that the tongue 16 substantially covers the groove or channel 22 in the upper ground strip, thereby providing a conduit or closed channel through which the conductor cord may pass from the raceway out through the outlet device. The cord is thereby protected against injury when the base board is replaced.

In the form of the invention illustrated in Fig. 6, the front flange below the hood portion 18^a is omitted and the lower end walls 21^a of the hood portion are bent laterally to form flanges 16^a adapted to rest on the top of the ground strip. Nail holes 23^a may be provided in the flanges 16^a through which tacks or brads may be driven into the ground strip to secure the outlet device thereto. Otherwise the device is identical with the other form above described. The advantage of the form illustrated in Fig. 6 is that no part of the device intervenes between the base board and ground strip. In each case the flange 17 or 17^a which is forced between the ground strip and wall, acts to secure the outlet device in place.

It will be observed that with the use of the present outlet device, the plastering of the room is not defaced whatsoever in running an extension cord from the raceway to the interior of the room. Furthermore, a plurality of such outlet devices may be provided along the length of the base board, which devices

are concealed by the surface finish of the wall, and any of which may be brought into use whenever desired, without marring the finish of the wall in any manner.

While I have shown and described the outlet in connection with a base board construction, it is obvious that it can be used in connection with other trim of a room, as, for instance, the chair rail or picture molding. I do not, therefore, desire to limit the use of the invention to a base board except as particularly specified in the appended claims.

More or less variation of the exact details of construction is possible without departing from the spirit of this invention. I desire, therefore, not to limit myself to the exact form of the construction shown and described, but intend, in the following claims, to point out all of the invention disclosed herein.

I claim as new, and desire to secure by Letters Patent:

1. An outlet for base board raceways comprising in combination a ground strip having a transversely extending groove, and an outlet member formed with a hood-like portion overlying an end of the groove in the ground strip, said hood-like portion having side and end walls and portions extending from certain of its walls and extending parallel with faces of said ground strip and secured thereto, there being an outlet opening in one side wall of said hood-like portion.

2. An outlet for base board raceways comprising in combination a ground strip having a transversely extending groove, and an outlet member formed with a hood-like portion overlying an end of the groove in the ground strip, said hood-like portion being formed with spaced side walls in the form of two tongues adapted to frictionally secure the outlet member upon the ground strip, and there being an outlet opening in one of said side walls.

3. An outlet for raceways comprising a hood-like member open at the bottom and having a top wall, end walls and at least one side wall, the latter terminating in the form of a tongue which extends below the end walls, and there being an outlet opening in a side wall leading from the cavity in the hood portion.

4. An outlet for base board raceways comprising a hood-like member open at the bottom and having a top wall, end walls and two side walls, said side walls terminating in the form of tongues that project below the end walls and converge toward each other, one of said side walls being formed with an outlet opening co-incident with the cavity in the hood.

5. An outlet for base board raceways comprising a hood-like portion having a top wall, end walls and two side walls, the latter being in the form of tongues which project

down from said top wall to a point below the end walls, and one of said tongues being formed with nail holes therein, there being an outlet opening in one of said side walls

5 leading from the cavity in the hood.

6. An outlet for raceways comprising a hood-like portion formed with a top wall, end walls and side walls, at least one of said walls being formed with extensions having

10 nail holes therein, and one of said side walls being formed with a knockout place co-incident

15 with the cavity in the hood.

7. An outlet for raceways comprising a hood-like portion open at the bottom and

15 having a top wall, end walls and side walls, one of said side walls being formed with a

knockout place co-incident with the cavity in

19 the hood, and at least one of said walls being

23 formed with an extension in the form of a

26 tongue provided with nail holes.
